(57) **CLAIM**

The ornamental design for a bean bag top member of an animal bed assembly, as shown and described.

DESCRIPTION

FIG. 1 is a top, front right perspective view of a first embodiment of a bean bag top member of an animal bed assembly shown according to the present design;

FIG. 2 is a bottom, front right perspective view thereof;

FIG. 3 is a front end view thereof;

FIG. 4 is a rear end view thereof;

FIG. 5 is a right side elevational view thereof;

FIG. 6 is a left side elevational view thereof;

FIG. 7 is a top plan view thereof;

FIG. 8 is a bottom plan view thereof;

FIG. 9 is a top, front right perspective view of a second embodiment of a bean bag top member of an animal bed assembly shown according to the present design;

FIG. 10 is a bottom, front right perspective view thereof;

FIG. 11 is a front end view thereof;

FIG. 12 is a rear end view thereof;

FIG. 13 is a right side elevational view thereof;

FIG. 14 is a left side elevational view thereof;

FIG. 15 is a top plan view thereof; and,

FIG. 16 is a bottom plan view thereof.

The broken line representations in the figures show unclaimed environment or boundaries. The broken line representations thus form no part of the claimed design as filed.

The broken lines in the figures illustrate portions of the bean bag top member of an animal bed assembly that form no part of the claimed design.

1 Claim, 12 Drawing Sheets
